FIG. 5.

INVENTOR:

Herbert A. Carhart

By Jacob Feltel

HIS ATTORNEY

UNITED STATES PATENT OFFICE.

HERBERT A. CARHART, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,195,557.

Specification of Letters Patent. Patented Aug. 22, 1916.

Application filed May 16, 1916. Serial No. 97,759.

To all whom it may concern:

Be it known that I, HERBERT A. CARHART, citizen of the United States, and resident of Syracuse, in the county of Onondaga and 5 State of New York, have invented certain new and useful Improvements in Type-Writing Machines, of which the following is a specification.

My invention relates to typewriting machines and more particularly to the work holding and feeding mechanisms of such machines.

My invention has for its principal object to provide improved means for holding and 15 feeding certain classes of work, especially envelopes and cards, including the sort of stencil cards that are used in addressing machines. I have provided an improved contrivance of this character which is simple 20 in construction, and which can be readily applied to existing machines without modifying the parts of said machines as heretofore manufactured, except by removing some of said parts bodily and substituting 25 my mechanism.

To the above and other ends which will hereinafter appear, my invention consists in certain features of construction and combinations and arrangements of parts, all of 30 which will be fully set forth herein and particularly pointed out in the claims.

In the accompanying drawings, Figure 1 is a left-hand side elevation of the upper rear part of a typewriting machine having 35 my invention embodied therein, the parts being shown in position for writing the uppermost line of the address on an envelop. Fig. 2 is a front elevation of the same. Fig. 3 is a view similar to Fig. 1 but with some 40 parts sectioned away and with the mechanism in the position it occupies when writing the lowermost line on the envelop. Fig. 4 is a fragmentary front elevation showing the parts in the same position as Fig. 3. Fig. 5 is an isometric view of the work 45 holder and guide and some parts of the platen frame, parts being broken away.

My invention can be adapted to various styles of typewriting machines, but I have 50 here shown it applied to a Smith Premier No. 10 typewriter. This machine comprises a top plate 1 having a stationary carriage rail 2 mounted on standards 3 on said top plate and grooved to receive anti-friction

balls 4 on which a carriage 5 is adapted to 55 travel by means of grooved rails constituting a part of the carriage. The machine includes a roller platen 6, the shaft 7 of which is journaled in end pieces 8 of a detachable platen frame, which frame also includes an 60 upper longitudinal rod 10 and a lower longitudinal rod 11, said rods connecting the two end pieces. Said platen frame is detachably mounted in the end brackets of the carriage by means of certain studs 12 projecting laterally from the end pieces 8 in a manner well known in the art and not necessary here to be further explained. The rods 10 and 11 are inserted in suitable holes in the end pieces 8 where they are secured 70 by pins 13. The platen is provided with the usual line space wheel 14 for coöperation with the usual line space mechanism. Said mechanism is not here shown in all its parts, but a detent roller 15, coöperating 75 with the wheel 14, is shown in Fig. 3, and a line space handle 40 is shown by broken lines in Fig. 2.

In the Smith Premier machine as usually manufactured, the ordinary paper feeding 80 devices are mounted on the rods 10 and 11, the usual paper apron and lower feed rolls being mounted on the rod 11 and the paper fingers on the rod 10. In the present instance these ordinary paper feed devices are 85 dispensed with or removed, which can be done by removing the pins 13 at one end of the platen frame and thereby removing one of the end pieces 8.

My work holder comprises two bands or 90 split rings 16 each of which embraces the platen but does not quite encircle it, a space 17 being left between the two ends of the ring. Each of these rings is elastic and in its natural state its internal diameter is 95 slightly less than the external diameter of the platen so that when it is put on the platen it embraces the latter tightly enough to hold it frictionally in place on the platen; but the rings can move with relation to the 100 platen by the exertion of a little force. The two rings or bands 16 are connected together by means of bars, a lower bar 18 and an upper bar 20 being shown in the present instance. Said bars extend longitudinally 105 of the platen and preferably are secured to the bands 16 at the ends of said bands, the bar 18 being secured just below the opening

17 and the bar 20 just above said opening; but said bars may be otherwise disposed. The rings or bands 16 and the bars 18 and 20 together constitute a frame frictionally held on the platen as shown. The bar 20 is preferably off-set at 21 toward the platen so that said bar is either actually or substantially in contact with the platen and said bar has a clip or clips 22 secured thereto and projecting upward therefrom a short distance. In the present instance I have shown several comparatively short clips extending across the bar 20 but this arrangement may be varied. The clips are preferably bent outward at their upper edges or extremities to facilitate the insertion of an envelop or card between said clips and the platen. In the present instance four clips are shown, the two middle ones being preferably made of thin spring metal each having legs 23 extending down across the bar 20 and near their lower ends secured to said bar by rivets 24. The metal is cut away to form or produce comparatively narrow and widely spaced legs or members and the rivets are put near the lower ends of said legs in order to afford a slight spring action to the clips. These spring clips may be curved in toward the platen as shown at 25 so as to get a sufficient frictional grip on the envelop or card. The two end clips are shown without this inward curve and these can be of stiffer material. It will be understood, of course, that the entire construction of these clips for holding the bottom edge of the envelop or card can be varied, though the construction disclosed has been found highly satisfactory in practice and is therefore preferred.

40 Coöoperating with the envelop or card holder above described is another frame mounted on the upper rod 10 of the platen frame. As here shown this frame comprises two arms 26 rigidly connected together by cross rods 27 and 28, which rods may be secured to the arms 26 in any suitable way as, for example, by being shouldered and riveted at their ends. Said arms 26 are preferably, but not necessarily, pivoted to the rod 10 so that the frame can be turned up away from the platen. Said rod 10 is formed with a groove 29 and the paper fingers are usually mounted on sleeves that are adjustable along said rod and each of which has a lug that enters said groove and a spring is provided that reacts between said sleeve and the paper finger to press the paper finger against the paper. Each of the arms 26 as here shown is made of sheet metal curving down in front of the platen but not in contact therewith and beneath the rod 10 it is formed with an arm or yoke piece 30 bent off horizontally therefrom and thence bent vertically to form an ear 31, which ear 65 is also pivotally mounted on the rod 10.

The frame can be spring-pressed toward the platen in any suitable way, various means suitable for the purpose being common in the paper fingers of typewriters. For example, between the arm 26 and the ear 31 a sleeve may be loosely mounted on the rod 10 and said sleeve may have a lug projecting therefrom into the groove 29. A spring 33 coiled about said sleeve may be connected at one end with said sleeve and at the other end said spring may bear against the yoke bar 30, the spring acting to press the arm 26 toward the platen. Each of said arms at its free end has an ear 34 bent off therefrom and bearing on one of the bands or rings 16 above the bar 20. In the present instance the arms 26 are spaced apart a distance a little less than said rings 16 and the ears 34 are therefore bent off toward the respective ends of the platen.

85 Any suitable stop device 35 is rigidly mounted on each of the bands 16, the one here shown consisting of a plate of sheet metal standing out from the ring and having feet 36 bent off therefrom and secured to the ring as, for example, by rivets. This stop device, as here shown, is made of such height that when the platen is turned toward the back of the machine it and the ring 16 will be arrested by contact of said device 35 with the bar 10 as shown in Figs. 3 and 5; and when the platen is turned toward the front of the machine said stop device is arrested after a suitable extent of travel by the lug 34. The stop devices are so disposed as to allow to the work-holder an extent of motion appropriate to the use to which the device is to be put. In the present instance the said device is used for writing addresses, an envelop 37 being shown in 105 the machine. In this case the envelop-holder has a maximum extent of movement sufficient for writing four lines with double line spacing; that is to say, it has a maximum extent of movement of eight teeth of 110 the line space wheel 14.

The cross rod 27 of the pivoted frame is a frame rod put in for mechanical reasons; but the rod 28 not only constitutes a frame rod but it also constitutes a guide rod for 115 the work piece and it is so disposed that the type on the type bars 38 of the typewriter will strike just beneath this rod.

120 The frame 26, 27, 28 can, of course, be rigidly mounted on the rod 10 and can be made adjustable lengthwise of said rod in any suitable way. It is, however, desirable that the rod 28 be held about the proper distance from the platen, and this is readily brought about by pivoting the frame and having it spring-pressed toward the platen, as shown, the free end of the frame, where the rod 28 is located, resting on the rings 16. Moreover, the construction actually adopted facilitates the adjustment of the frame 130

lengthwise of the platen, said frame being thus adjustable by merely sliding it along the rod 10 in the same way that paper fingers are adjusted. If said frame were rigidly mounted on the rod 10, but with provision for adjustment along said rod, the groove 29, or other securing means, would require to be located with accuracy and the parts would have to be fitted with nicety in order to hold the bar 28 at the right distance from the platen. With the parts constructed as shown, all this precision is rendered unnecessary. Moreover, the springs provide friction to retain the frame in its adjusted position, they prevent rattling, and they allow the frame to yield in case very stiff cards are written on.

It will be understood that the frame 16, 18, 20 is also adjustable both lengthwise of the platen and also around the platen, the rings being adapted to slip on the platen upon the exertion of a little force. The adjustment around the platen can be effected by merely forcing the platen to turn after the rings have been arrested at one end or the other of their excursion; and the rings with their bars 18 and 20 and the frame 26, 27, 28 can be adjusted together lengthwise of the platen. As the arms 26 are arranged between the stop-pieces 35, endwise pressure against either frame will carry the other with it lengthwise of the platen. It will be, of course, understood that these adjustments are for the purpose of using different parts of the surface of the platen so that the wear on the platen will not all come at one place but can be distributed over the surface thereof.

The arms 26 can be utilized, if desired, as side edge guides for the work pieces so that all of said work pieces can be inserted in the machine in exactly the same way for the sake of uniformity in the writing. This will be especially useful if the machine is equipped with a tabulator. A part of the ordinary tabulator of the Smith Premier machine is shown in Fig. 1 at 41.

In operation, the platen is turned toward the back of the machine until the work holder has been carried as far up as it will go, that is to say, to the position shown in Figs. 3 and 4. The envelop is then inserted by the mere act of pushing it down between the platen and the rod 28 until the lower edge of the envelop comes behind the clips 22 and is arrested by the upper edge of the bar 20 which bar acts as an end stop for the work piece. The platen is then turned toward the front of the machine, by manipulation of one of the finger wheels 39, to the position shown in Figs. 1 and 2 where it is ready for writing the first line as shown in Fig. 2. The platen is then turned by means of the line space handle 40 to the position for writing the second line and by the same

means to write the third and fourth lines. When the fourth line has been written the envelop and holder stand as shown in Figs. 3 and 4. The envelop is then withdrawn from the holder and another envelop is set into place and the platen turned back to write the first line as before.

It will be noted that the device is of very simple construction and that in putting it on the machine no structural changes whatever are required to be made in said machine. The work holder is merely sprung over the platen and slipped along to a suitable position thereon and the upper frame 26, 27, 28 is slipped on the rod 10 in the same way as the paper fingers. This makes the device extremely easy to manufacture as any platen frame can be made up with this device on it without making any difference in the process of manufacture of said frame; and it is within the power of a repairman to remove the ordinary paper feed devices from a platen frame that has been equipped therewith and to substitute the devices herein shown and described. Moreover, the device is extremely convenient in use, enabling writing of the character for which it is adapted to be effected with a maximum of convenience and rapidity and with entire uniformity. It will be noted that the envelop is removed from the device by merely pulling it out and that the operation of inserting a new envelop consists simply of one movement, namely, the envelop is pushed down behind the rod 28 until arrested by the bar 20.

Various changes can be made in the details of construction and arrangement without departing from my invention.

What I claim as new and desire to secure by Letters Patent, is:—

1. In a typewriting machine, the combination with a rotatable platen, of a work holder frictionally held on said platen so as to turn with the platen but capable of slipping on the platen, and arresting means for said work holder.

2. In a typewriting machine, the combination with a platen, of a work holder frictionally mounted on the platen so as to turn therewith but capable of being slipped on and relative to the platen, and means for limiting the rotatory motion of said work holder in two directions.

3. In a typewriting machine, the combination with a platen and platen frame, of a work holder comprising two split rings and a connecting cross bar, and clips on said cross bar, said split rings frictionally embracing said platen; and a work guiding and work-holder-arresting frame mounted on said platen frame.

4. In a typewriting machine, the combination with a platen and platen frame, of a work holder comprising two rings embrac-

ing said platen and a connecting cross bar, stops on said rings, coöperating stop devices, and a transverse work-guiding rod.

5. In a typewriting machine, the combination with a platen and a platen frame, of a work holder comprising two rings embracing said platen and a connecting cross bar, stop devices on said rings, and a coöperating frame having stops for coöperation with 10 said stop devices and having also a work-guiding bar.

6. In a typewriting machine, the combination with a platen and a platen frame, of a work holder comprising two rings embracing 15 said platen and a connecting cross bar, stop devices on said rings, and a coöperating frame having stops for coöperation with said stop devices and having also a work-guiding bar, said work holder and said 20 frame being adjustable lengthwise of the platen.

7. In a typewriting machine, the combination with a platen and platen frame, of a work holder mounted on said platen and 25 adjustable lengthwise thereof, and a pivoted frame mounted on said platen frame and adjustable lengthwise of said platen and spring-pressed against said work holder, said pivoted frame including a work-guiding 30 bar.

8. In a typewriting machine, the combination with a platen, of a work holding device comprising a longitudinally arranged bar supported by the platen in position to 35 serve as an end stop for a work-piece, and a spring clip having a continuous plate-like portion and depending resilient spaced members, said members secured to the face of said bar and said plate-like portion projecting 40 beyond the bar in position to engage said work-piece.

9. In a typewriting machine, the combination with a rotary platen, of work feeding means comprising two frames, one of 45 which is integral and self-gripping on the platen so as to turn therewith, and the other of which is relatively stationary, and stops carried by both said frames.

10. In a typewriting machine, the combination of a carriage frame, a platen mounted to rotate therein, work feeding means comprising two frames, one of which is mounted frictionally on the platen, and the other of which is mounted on the carriage 55 frame, and stops carried by both said frames.

11. In a typewriting machine, the combination of a carriage frame, a rotary platen, a work holding frame frictionally mounted 60 on the platen, and a coöperating pivoted spring-pressed frame frictionally mounted on the carriage and comprising a work-guiding bar 28 extending across the face of the work, both said frames being mounted 65 for simultaneous adjustment lengthwise of

the platen, and one of said frames being adapted for adjustment circumferentially of the platen.

12. In a typewriting machine, the combination of a carriage frame, a platen mounted to rotate therein, a work holding frame frictionally mounted on said platen, and a coöperating frame frictionally mounted on the carriage frame and comprising a work-guiding bar 28 extending across the face of 75 the work, said two frictionally mounted frames interlapping and adjustable together as one.

13. In a typewriting machine, the combination of a carriage frame, a platen mounted 80 to rotate therein, a frame frictionally mounted on said platen, a spring pressed frame frictionally mounted on the carriage frame and comprising forwardly extended arms arranged between upstanding stop devices on the first mentioned frictionally mounted frame.

14. In a typewriting machine, the combination of a carriage frame, a platen mounted to rotate therein, a work holding frame 90 mounted on said platen and provided with upstanding stop members, a supplemental frame mounted on the carriage frame and having forwardly extended arms provided at their free ends with stops to engage the 95 stop devices on the first mentioned frame when the platen is rotated backwardly.

15. In a typewriting machine, the combination of a carriage frame comprising a longitudinally extending bar, a frame mounted 100 on said bar and comprising forwardly extended arms provided at their extremities with stops, a platen, and a work holding frame thereon provided with coöperating stops.

16. In a typewriting machine, the combination of a carriage frame, comprising a longitudinally extending bar, a frame mounted on said bar and comprising forwardly extending arms one at least of which is provided with a stop at its extremity, a platen mounted to rotate in said carriage frame, a work holder mounted on said platen and provided with a duplex stop member, one stop of said member being adapted to engage the said carriage bar, and the other stop being adapted to engage said stop at the extremity of the said forwardly extended arm.

17. In a typewriting machine, the combination of a carriage frame; a rotary platen therein; a frame comprising two incomplete spring rings, two parallel bars connecting the ends of said rings, clips on one of the said bars, and stop devices on said rings; 110 and a supplemental frame mounted on the carriage frame and comprising forwardly extended arms, a guide bar connecting said arms and also stop devices to engage the stop devices on the rings.

18. The combination of a platen, a platen frame, a frame pivotally mounted on the platen frame and including a transverse work-guiding bar, spring means for pressing said pivoted frame toward the platen, and means for limiting the motion of said frame under the pressure of said spring means so as to hold said bar out of contact with said platen.
- 10 19. The combination of a platen, a platen frame, a frame pivotally mounted on the platen frame and including a transverse

work-guiding bar, spring means for pressing said pivoted frame toward the platen, means for limiting the motion of said frame 15 under the pressure of said spring means so as to hold said bar out of contact with said platen; and a coöperating work-holder mounted on said platen.

Signed at Syracuse, in the county of 20 Onondaga and State of New York, this 12th day of May, A. D. 1916.

HERBERT A. CARHART.
